UNITED STATES PATENT OFFICE.

DELOSS PALMER, OF CHICAGO, ILLINOIS, ASSIGNOR TO CRAGIN BROTHERS
& CHANDLER, OF SAME PLACE.

SOLDERING-TOOL.

SPECIFICATION forming part of Letters Patent No. 223,945, dated January 27, 1880.

Application filed September 30, 1879.

To all whom it may concern:

Be it known that I, DELOSS PALMER, of Chicago, in the county of Cook and State of Illinois, have invented a new and useful Improvement in Soldering-Tools, of which the following is a specification, reference being had to the accompanying drawings.

The nature of my invention relates to devices for soldering tin cans; and it is my object to provide a tool in which the soldering metal can be melted, and by means of which it can be supplied to the several cans in a fused condition and in uniform quantities, this device being particularly intended to be used in combination with the apparatus for soldering tin cans which I have described in the specification forming part of my separate application.

My invention consists of an iron funnel having a handle to its mouth end, and being arranged in its bottom end with a double valve operated from a bell-crank arm which is pivoted to the side of the handle. Each depression of this arm will change the position of the valves for discharging a certain amount of soldering metal, which is melted in said funnel by a gas-jet and air-blast attached to the side of the same.

In the drawings, Figure 1 represents an elevation of the soldering-tool; Fig. 2, a longitudinal vertical section of the same; Fig. 3, a section on line *x* *x*, and Fig. 4 a section on line *y* *y*, of Fig. 2.

Like letters in the several figures of the drawings designate like parts.

A denotes a slender cast-iron funnel, having flange *a* to its upper edge for securing to it the wooden handle *B* by an eyebolt, *C*, and screw-nut *c*. The lower end of this handle *B* is inserted in a thimble, *D*, having lugs *d*, between which is pivoted the apex of a bell-crank, *E*. The longer arm of this bell-crank *E* stands about parallel with the handle *B*, and is held off by a leaf-spring, *e*, which extends from thimble *d*, and the short rectangular arm of the bell-crank has a bifurcated end and is pivotally connected with valve-rod *F*.

The lower end of funnel *A* is cast solid, and is bored and counterbored for forming a cylindrical chamber, *g*, with an upward valve-seat,

and the lower end of this chamber is internally screw-threaded for coupling therewith a nipple-shaped plug, *H*, the upper end of which being screw-threaded. This plug *H* is bored out centrally from its top to form a socket, *h*, 55 therein, which is countersunk on its upper end for forming a valve-seat, and a small vent, *i*, is drilled through the remaining wall to the bottom of said socket at an angle of about forty-five degrees therewith. 60

The lower extremity of rod *F* carries two conical valves, *f* and *f'*, one of which is to fit the seat in the upper end of chamber *g* and the other one to fit the seat in plug *H*, and both these valves are placed such a distance 65 apart that only one at a time can close upon its seat, while the other one is held in suspense. The action of spring *e* against bell-crank arm *E* will press the lower valve, *f'*, upon its seat, and by pulling said arm *E* toward the handle *B* so as to compress said spring *e* the valve *f'* will be raised off its seat and the valve *f* will be closed. 70

With the above arrangement each operation on the valves will discharge through vent *i* a 75 determined measure of fused metal equal to the capacity of chamber *g*.

Opposite to handle *B* the funnel *A* has a semicircular groove, which is formed longitudinally in its wall, and extends from near its 80 top to the valve-chamber portion of said funnel. Into the upper half of this groove is secured one shank of an elbow-shaped pipe, *J*. A smaller pipe, *j*, which is also elbow-shaped, pierces the pipe *J* at its curved point, and extends inside thereof to near its end. This pipe *j* is to be connected by a hose or flexible pipe with a gas-supply pipe, and the larger pipe *J* is to furnish a sufficient current of atmospheric air to the ejected gas, either by natural draft 85 or by flexibly connecting it with a blower. The air and gas thus thoroughly mixed will produce a long smokeless flame for heating the funnel. 90

The lower half of the funnel *A* is covered by 95 a sheet-metal sleeve, *L*, having a semi-cylindrical bulge, *l*, which covers the groove in the funnel-wall and forms a round flue therewith, and exteriorly its whole length this bulge *l* is perforated with a row of small holes, and with 100

a larger opening in its bottom end, for providing a free outlet for the products of combustion of the burning gases blown through this flue.

5. By means of the eye C to the end of its handle the tool is to be suspended to the end of a cord or chain passed over pulleys, and having a counter-weight to its opposite end, that the tool may be raised and lowered with ease, and 10 that it will be hoisted out of the way when not in use.

After filling the funnel A with soldering metal and turning on and igniting the gas-jet, said metal will melt and will be kept at 15 the fusing-point, when the operator, by taking hold of the handle B for directing the tool, with every compression upon the bell-crank arm E, can discharge a uniform amount of metal into a can to be soldered.

20. In locations where gas cannot be had the funnel may be heated by a different device for fusing the metal therein.

Having thus described my invention, what I claim as new, and desire to secure by Letters Patent, is—

25. 1. In a tool for melting solder and dropping it in regular quantities, the combination, with the funnel A, of the air and gas pipes J j, attached to the side of such funnel, the gas pipe

terminating within the end of the air-pipe, 30 substantially as and for the purposes set forth.

2. In a tool for melting solder and dropping it in regular quantities, the combination, with the funnel A, of the gas and air pipes J j, terminating one within the other at the side of 35 the funnel, and the perforated sleeve L, placed around such funnel and over the end of the gas and air pipes, for the purpose of heating the funnel, substantially as described and shown.

3. The funnel A, having handle B, bell-crank E, spring e, rod F, with valves f f', chamber g, and socketed plug H, with vent i, the same being constructed and arranged to operate substantially as and for the purpose 45 set forth.

4. In combination with the funnel A, having handle B, bell-crank E, spring e, rod F, with valves f f', chamber g, and plug H, with socket h and vent i, the gas and air pipes J J 50 and collar L, with perforated bulge l, the whole of which being constructed and arranged to operate substantially as and for the purpose described and shown.

DELOSS PALMER.
